J. ENDERLIN, JR.
TOOL FOR DETACHING PUPPET VALVES FOR GRINDING, CLEANING, OR OTHER PURPOSES.
APPLICATION FILED FEB. 7, 1916.

1,200,179.

Patented Oct. 3, 1916.

UNITED STATES PATENT OFFICE.

JOSEPH ENDERLIN, JR., OF NORTHPORT, NEW YORK.

TOOL FOR DETACHING PUPPET-VALVES FOR GRINDING, CLEANING, OR OTHER PURPOSES.

1,200,179.

Specification of Letters Patent.

Patented Oct. 3, 1916.

Application filed February 7, 1916. Serial No. 76,562.

To all whom it may concern:

Be it known that I, JOSEPH ENDERLIN, Jr., a citizen of the United States, and residing at Northport, Long Island, in the county of Suffolk and State of New York, have invented certain new and useful Improvements in Tools for Detaching Puppet-Valves for Grinding, Cleaning, or other Purposes, of which the following is a specification, such as will enable those skilled 10 in the art to which it appertains to make and use the same.

This invention relates to tools for use in detaching the puppet valves of internal combustion and other engines for the purpose of grinding and cleaning or repairing said valves, and the object thereof is to provide an improved tool of this class which is simple in construction, efficient in 20 operation and which can be easily manipulated for the purpose specified.

The invention is fully disclosed in the following specification, of which the accompanying drawing forms a part, in which 25 the separate parts of my improvement are designated by suitable reference characters in each of the views, and in which:—

Figure 1 is a side view of my improved tool indicating the method of its use; and, 30 Fig. 2 a side edge view of the tool detached looking in the direction of the arrow 2 of Fig. 1.

In the drawing forming part of this specification, I have indicated at *a* a part of 35 the cylinder of an internal combustion or other engine and at *b* an ordinary puppet valve provided with a stem *c*, and at *d* I have shown a part of the support for the operative means of the valve, part of which 40 is shown. I have also shown at *e* a part of the valve operating means and on which the end of the stem *c* of the valve normally rests, and mounted on the stem *c* is a cup-shaped disk *f* between which and the cylinder *a* is placed the usual spiral spring *g* 45 which bears on said disk, and said disk is held in its proper position by a stop pin *h* passed through said stem. All this construction is old and may be of the usual or 50 any preferred form.

In the construction of my improved tool I provide a yoke-shaped handle member *i* through the cross head portion *i*² of which is passed a screw *j* provided at its outer end 55 with a thumb nut *k*, and pivoted between

the ends of the side portions of the yoke-shaped handle member *i*, as shown at *i*³, are two levers *m* which operate between the sides of the yoke-shaped handle member *i* and the outer ends of which are provided 60 with jaws *m*² having forked heads *m*³.

The inner ends of the levers *m* are curved outwardly as shown at *m*⁴, and pivotally connected therewith as shown at *m*⁵ are links *n* which are pivotally connected at *n*², and 65 the screw *j* is provided at its inner end with a flat head *j*² through which the pivot pin at *n*² passes. With this construction the thumb nut *k* may be turned and moved outwardly on the screw *j* in order to permit 70 the jaws *m*² to be brought approximately together, and when said jaws are in this position one of them is placed on the support *d* of the means for operating the puppet valve and the other under the disk *f* as 75 shown in Fig. 1, after which the nut *k* is turned and moved inwardly on the screw *j*, and this operation draws the inner ends of the levers *m* together and forces the jaws *m*² apart, and this operation releases the 80 tension of the spring *g* and the pin *h* may be removed and the valve *b* may be removed or detached for grinding, repairing and other purposes. The replacement of the 85 valve *b* will be the reverse of that above described, the valve stem being first inserted after which the spring *g* is placed in position and the disk *f* mounted on the stem *c*, after which the tool is operated to raise said disk against the pressure of the spring *g* 90 in order to permit of the insertion of the pin *h*, and in both of the described operations it will be understood that the stop pin *h* is movable through the forked head *m*³ of the upper jaw member *m*², and it will also be 95 observed from Fig. 2 of the drawing that the head *m*³ of the upper jaw member is wider than the head *m*³ of the lower jaw member. The aperture *i*⁴ in the head of the yoke-shaped handle member through which 100 the screw *j* passes is large enough to permit said screw to swing freely within certain limits in the plane of the levers *m* and this will permit of the manipulation of said screw so as to swing the inner ends *m*⁴ of 105 said levers and the links *n* laterally so as to facilitate the operation of the device when any parts of the engine, or the framework thereof are in position to interfere with the operation of the tool.

The method of operating my improved tool will be readily understood by all those familiar with puppet valves, the method of their mounting and the means employed for detaching the same for various purposes; and while I have shown and described the construction of my improved tool which I prefer, my invention is not limited to the exact details of construction herein shown and described, and changes therein and modifications thereof may be made, within the scope of the appended claims without departing from the spirit of my invention or sacrificing its advantages.

Having fully described my invention, what I claim as new and desire to secure by Letters Patent, is:—

1. A tool of the class described comprising a yoke-shaped handle member, a screw 20 passing through the head thereof, levers pivoted between the ends of the sides of said handle member and provided at their outer ends with jaws having forked heads, and links connected with the inner ends of said levers and with said screw.

2. A tool of the class described comprising a yoke-shaped handle member, a screw passing through the head thereof, levers pivoted between the ends of the sides of said handle member and provided at their outer ends with jaws having open heads, and links connected with the inner ends of said levers and with said screw.

3. A tool of the class described, comprising a yoke-shaped handle member, levers 35 pivoted in one end thereof and provided at their outer ends with open jaws, and means adjustably mounted in the other end of said handle member and in operative connection with the inner ends of said levers 40 for operating said jaws to open and close the same.

In testimony that I claim the foregoing as my invention I have signed my name in presence of the subscribing witnesses this 4th 45 day of February 1916.

JOSEPH ENDERLIN, JR.
